UNITED STATES PATENT OFFICE.

OTHO C. DURYEA, OF LOS ANGELES, CALIFORNIA, ASSIGNOR OF ONE-HALF
TO MORRIS C. WHITE, OF SAME PLACE.

OIL-CUP.

SPECIFICATION forming part of Letters Patent No. 684,767, dated October 15, 1901.

Application filed December 1, 1900. Serial No. 38,330. (No model.)

To all whom it may concern:

Be it known that I, OTHO C. DURYEA, a citizen of the United States, residing at Los Angeles, in the county of Los Angeles, State of California, have invented new and useful Improvements in Oil-Cups for Feeding Oil to the Cylinders of Explosive-Engines, of which the following is a specification.

The object thereof is to provide a simple and inexpensive oil-cup which will automatically feed the oil to the cylinder while the engine is in operation. I accomplish this object by means of the mechanism illustrated in the accompanying drawing, being a central vertical section of my improved oil-cup, a part of the cylinder of the engine to which it is secured being shown.

The oil-cup A is attached to the cylinder B' in the usual manner by being screwed therewith, care being taken that the threaded shank of the oil-cup does not project down into the piston-chamber and contact with the piston in its movement along the cylinder. The opening in the cylinder for the oil-cup is immediately over the piston when the piston is at the outer limit of its stroke. Running down through the center of the oil-cup and through the center of the shank thereof I provide a cylindrical tube B, the bottom 30 opening directly into the piston-chamber and the top projecting up into the oil-cup and terminating in a hemispherical valve-seat C'. In this tube I provide two valves, one in the top and one in the bottom. In the top of the tube I place a spherical valve-stopper C, which rests on the valve-seat C' and permits the gas to pass up through the tube from the piston-chamber into the top of the oil-cup, which occurs when the piston reaches its 40 outer stroke, (because of the pressure of the gas in the tube while the piston is in this position caused by the escape of gas by the piston, a portion of which passes into the tube,) where it becomes entrapped when the valve-stopper drops into the valve-seat, which it does immediately the piston moves from under the oil-cup opening in the cylinder. Extending across the opening above the valve-stopper I place a removable bar D to limit 50 the movement of and prevent the accidental displacement of the stopper. The lower end

of the tube is securely screwed into the threaded socket in the bottom of the oil-cup. Within this screw-threaded socket in the oil-cup I place a spiral spring E. On the top of this 55 spring I place a conical valve-stopper F, having an opening through the center. In the lower part of the tube I provide a conical valve-seat G to engage the valve-stopper F. Through this valve-seat I provide valve-ports 60 G' for the passage of oil. The valve-stopper F is held in normal engagement with the valve-seat G by the pressure thereon of the spiral spring, closing the ports therein. Now when the pressure of the gas (having entered through the tube from the piston-chamber to the oil-cup) creates a greater pressure on the oil in the cup than the combined resistance afforded by the spring and the pressure of the outer air on the under part of the 65 valve-stopper, which will happen when the piston has moved from under the oil-cup opening in the cylinder, leaving the under face of the valve-stopper F exposed to the outer air, it will cause the valve-stopper F to compress 70 the spring and cause it to recede from its seat G, leaving the ports in the seat open for the passage of oil therethrough down into the piston-chamber. Oil may be fed to the cup by removing from the top thereof the screw-cap 75 H. In the top of the tube I provide notches to engage the end of a screw-driver, by the rotation of which the tube can be raised or lowered in its seat in the socket of the oil-cup, and thereby compress or loosen the spiral 80 spring and increase or decrease the pressure of the valve-stopper F on the valve-seat G, and thereby regulate the feed of the oil to the cylinder.

Having described my invention, what I 90 claim as new, and desire to secure by Letters Patent, is—

1. An oil-cup, comprising a casing, adapted to be screwed into the piston-cylinder of an explosive-engine, and having a screw-threaded 95 socket in the bottom thereof for the reception of the shank of the central gas-conducting tube; a central gas-tube in said casing, having a conical valve-seat at the bottom thereof, with ports therethrough for the passage of 100 oil; and a hemispherical valve-seat in the top of said tube forming a seat for a spherical

valve-stopper; a spherical valve-stopper in said seat; a coiled spring in said socket; a conical valve-stopper on said coiled spring having an opening in the center thereof, adapted to engage the conical valve-seat in the tube; and means to compress or loosen said spring.

2. The combination with the cylinder of an explosion-engine, of an oil-cup comprising a main casing A, adapted to be screwed into a threaded opening in the cylinder; a tube B projecting from the bottom of said casing; a valve-seat in the top of said tube; a spherical valve-stopper C in the top of said tube and adapted to engage the valve-seat therein; the conical valve-stopper F in the bottom thereof, adapted to engage a valve-seat G on the bottom of the tube; a valve-seat G in said bottom; valve-ports in said valve-seat; a spiral spring E in said recess adapted to support and press the valve-stopper F up and against the valve-seat; and means to compress or loosen said spring to regulate the feed of oil to the cylinder.

3. An oil-cup to automatically feed oil to the cylinder of an explosive-engine, comprising an oil-cup secured to said cylinder; a tube in said oil-cup; valvular means in said tube to permit the products of explosion to pass through said tube into the cup above the oil and prevent its escape therefrom and thereby create a pressure thereon; a valve in the lower end of said tube to regulate the passage of oil therethrough; a stopper for said valve; a spring in the tube adapted to normally close the said stopper in said valve and prevent the passage of oil therethrough except when the pressure on the oil exceeds the combined pressure of said spring and of the outer air on the under side of the said valve-stopper.

In witness that I claim the foregoing I have hereunto subscribed my name this 21st day of November, 1900.

OTHO C. DURYEA.
